COMBINED PICTURE FRAME AND MIRROR

Lloyd S. Kyle, Sr., Vermilion, Ohio

Application August 10, 1955, Serial No. 37,406

Term of patent 14 years

(Cl. D29—20)

Fig. 1 is a front elevational view of a combined picture frame and mirror, showing my new design, the rear being substantially plain; and

Fig. 2 is a side elevational view thereof.

The dotted line representation is for the purpose of illustration only.

I claim:

The ornamental design for a combined picture frame and mirror, as shown and described.
